A. P. KERN

OIL BURNER

Filed March 24, 1923

FIG. 2.

A. P. Kern

INVENTOR

BY Victor J. Evans

ATTORNEY

E. Q. Rupprecht.

WITNESS:

UNITED STATES PATENT OFFICE.

ANTHONY P. KERN, OF ARGONIA, KANSAS.

OIL BURNER.

Application filed March 24, 1923. Serial No. 627,460.

To all whom it may concern:

Be it known that I, ANTHONY P. KERN, a citizen of the United States, residing at Argonia, in the county of Sumner and State of Kansas, have invented new and useful Improvements in Oil Burners, of which the following is a specification.

This invention relates to hydro-carbon burners, for use in various arts and for many purposes and has for its object the provision of a novel burner for using oil as a fuel, the burner being equipped with means for heating the fuel and consequently increasing its combustibility by converting it into a species 10 of vapor.

Another object is the provision of a device of this character in which the preheating pipe is out of the direct line of the flame which issues from an adjustable orifice, a 20 spreader being also provided against which the flame impinges.

An additional object is the provision of a burner of this character which will be simple and inexpensive in manufacture, highly 25 efficient in use, durable in service and a general improvement in the art.

With the above and other objects and advantages in view the invention consists in the details of construction to be hereinafter 30 more fully described and claimed and illustrated in the accompanying drawings, in which:

Figure 1 is a side elevation of the device and

Figure 2 is a cross section on the line 2—2 of Figure 1.

Referring more particularly to the drawings I have shown my device as comprising a main upper pipe 10 carrying at one end a 40 reducing nipple 11 connected with the fuel line 12, and having its other end carrying an elbow 13 which is in turn connected with a second elbow 14 screwed onto one end of a preheating pipe 15 which is located below the pipe 10. The opposite end of this pipe 45 15 carries an elbow 16 screwed onto a second elbow 17 connected with a pipe 18 which has its other end closed by a cap 19.

Threaded through the pipe 18 is a threaded rod or stem 20 which has a pointed upper end 21 engaging through a hole 22 in the uppermost point of the pipe 18. This hole 50 22 constitutes the jet and by turning the stem 20 the size of the hole is regulated for varying the feed of fuel. The lower end of this stem carries a beveled gear 23 with which

meshes a bevel gear 24 carried by one end of a shaft 25 which has a flexible connection 26 with an operating handle 27. By turning the handle 27 the stem 20 is adjusted to regulate the size of the jet. 60

Mounted below the pipe 18 is a priming pan 28 which may contain any desired absorbent material, or not, and which is designed to be filled with oil and lighted for 65 the purpose of initially heating the pipe 18.

Located below the pipe 10 is a flame spreader which consists of a plate 29 carried by two bolts 30 which are disposed at opposite sides of the pipe 10 and which pass 70 through a clamp 31 engaging the pipe. It should be stated that the pipe 15 is offset with respect to the pipes 10 and 18 so as to be out of the direct line of the flame.

In the operation of the device the stem 20 75 is initially turned to open the hole 22 a trifle so that oil may drip down and fill the priming pan 28. The oil within this pan is then ignited and when it burns it will heat the pipe 18 and start vaporization of the fuel 80 therein. When the pipe 18 becomes good and hot the valve 20 is again opened and the vapors issuing from the hole 22 are ignited. The flame shooting upwardly impinges against the spreader plate 29 and while the 85 pipe 15 is offset so as to be out of the direct line of the flame, it is quite obvious that it will nevertheless become thoroughly heated so that the oil in the whole system will be readily vaporized and made highly combustible. 90

From the foregoing description and a study of the drawings it will be apparent that I have thus provided a simply constructed and consequently inexpensive oil 95 burner which will utilize crude oil or distillate to equal advantage and which will be economical in fuel consumption while producing a very intense and effective heat.

While I have shown and described the 100 preferred embodiment of the invention it is of course to be understood that I reserve the right to make such changes in the form, construction and arrangement of parts as will not depart from the spirit of the invention or the scope of the subjoined claim. 105

Having thus described my invention I claim:

An oil burner comprising a pipe into one end of which leads a fuel line, a preheating 110 pipe located below and offset laterally with respect to said first named pipe and connect-

ed with the end thereof, a third pipe disposed below and connected with the end of said preheating pipe and having its free end closed, said last named pipe being provided at its uppermost point with an outlet hole, a needle valve screwed through said last named pipe and having a conical end projecting into and regulating the size of said hole, a priming pan surrounding the needle

valve located below said last named pipe, a ¹⁶ clamping member engaging the first named pipe and carrying a pair of depending bolts straddling the pipe, and a spreader plate carried by said bolts and located in line with and above the hole. ¹⁵

In testimony whereof I affix my signature.

ANTHONY P. KERN.
